Primary Examiner — Rosemary K Tarcza*(74) Attorney, Agent, or Firm* — Morgan, Lewis & Bockius LLP(57) **CLAIM**

We claim the ornamental design for a charging holder for mobile phones, as shown and described.

DESCRIPTION

FIG. 1 is a perspective view of a charging holder for mobile phones showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view showing the state of use.

The broken lines shown in the drawings are included for the purpose of illustrating environmental structure and form no part of the claimed design.
